UNITED STATES PATENT OFFICE.

NATHANIEL BALDWIN, OF EAST MILL CREEK, UTAH.

TELEPHONE RECEIVER.

Application filed February 19, 1926. Serial No. 89,430.

The present invention appertains to telephone receivers of the class in which an electrically operated armature is fulcrumed within the spool containing the actuating coil and is operatively connected with a diaphragm.

The object is to provide a simple, efficient and durable fulcrum for such armatures that will not get loose nor rattle.

10 I attain this object by the mechanism illustrated in the accompanying drawing in which Fig. 1 is an elevation of a spool containing the armature with the improved fulcrum device, Fig. 2 is a section of the same 15 spool along the line A B of Fig. 1; Fig. 3 is a plan view of the armature and fulcrum device; Fig. 4 is an elevation of a spool containing a modified form of the fulcrum device shown in Figs. 1, 2 and 3; Fig. 5 is a 20 section of the same spool along the line C D of Fig. 4; and Fig. 6 is a plan view of the armature and modified fulcrum device.

In the several figures of the drawing numeral 1 designates the spool within which 25 a fulcrum is provided for the armature 2. This fulcrum preferably may be a loop of wire 3, the ends of which are soldered or otherwise secured to the central tubular portion 4, of the spool. A spring 5 preferably 30 made of wire in an S-shape placed between the armature and tubular portion 4 of the spool is so shaped as to produce tension on the fulcrum wire loop 3. The purpose of the spring 5 is to keep the armature firmly 35 in contact with the fulcrum wire loop 3 and prevent rattling.

The spring 5 shown in Figs. 4, 5, and 6

is modified in shape and designed to exert a force on the armature tending to tip it and produce tension on the diaphragm through 40 the link 6. This form of spring may be used with such forms of diaphragms as require tension and thus serve a double purpose.

I claim—

1. In a telephone receiver of the class described, a spool having a tubular center, an armature within said tubular spool center, fulcrum wires supporting said armature within said tubular center and a spring within said tubular center adapted to put 50 tension on said fulcrum wires.

2. In a telephone receiver of the class described, a spool having a tubular center, an armature within said tubular spool center, fulcrum wires supporting said armature within said tubular center and a wire spring within said tubular center adapted to put 55 tension on said fulcrum wires.

3. In a telephone receiver of the class described, a spool having a tubular center, an armature within said tubular spool center, fulcrum wires supporting said armature within said tubular center, a wire spring within said tubular center adapted to put 60 tension on said fulcrum wires and adapted to tip said armature upon its fulcrum.

4. In a telephone receiver of the class described, a spool having a tubular center, an armature within said tubular center, a fulcrum for said armature and a spring within 70 said tubular center pressing said armature against said fulcrum.

NATHANIEL BALDWIN.
